TORPEDO STEERING MECHANISM

Dwight L. Supernaw, Key West, Fla., assignor to the United States of America as represented by the Secretary of the Navy

Filed Mar. 27, 1956, Ser. No. 152,087

2 Claims. (Cl. 114—23)

This invention relates to guided missiles and more particularly to a mechanism for operating the azimuth steering engine of a torpedo, such that the position of the rudder of the torpedo is governed either by a gyroscope or in accordance with acoustic signals emanating from a target vessel, thereby to guide the torpedo toward and to strike the vessel.

According to the arrangement of the present invention the torpedo is provided with the usual gyroscopic steering control which operates to guide the torpedo, in the absence of a satisfactory acoustical signal, to maintain the torpedo traveling in a prearranged direction, for example in the direction in which it is launched. When the torpedo has started on the target run under control of the gyroscope and thereafter a satisfactory acoustic signal is received by the alternate steering device, the rudder control mechanism is then transferred from gyroscopic influence to control by an acoustic steering system which is responsive to signals emanating from the target vessel, such, for example, as propeller or ship noises, the acoustic system and the mechanism for operating the azimuth steering engine being effective to guide the torpedo to the vessel without causing precession of the gyroscope during the period controlled by the acoustical steering system.

The acoustic steering system forms no part of the present invention and any suitable acoustical steering device may be employed for the purpose. Such a system, for example, is disclosed and claimed in the Patent No. 1,588,932 issued on June 15, 1926 to Robert S. Blair for Art and Apparatus for Warfare. In this patent a pair of hydrophones are mounted in the forward portion of the torpedo in a common horizontal plane on opposite sides of the torpedo center line. The hydrophones are responsive to acoustical vibrations within a predetermined frequency range, and operate a circuit whose output may be utilized for controlling the azimuth position of the torpedo rudder according to which one of the hydrophones receives the strongest signal from the target vessel.

The foregoing dual acoustic and gyroscopic control is accomplished by providing a yieldable link between the gyroscope axis position-sensing pellet mechanism and the steering engine operating mechanism, such that the link can be operated under control of the gyro in the absence of acoustic signals. When acoustic signals are received, however, the link portion operates in response only to the signals, the yieldable connection avoiding accompanying movements of the gyroscope mechanism and resultant precession of the gyroscope. By reason of this arrangement the gyroscopic control system is effectively "overridden" by the acoustic control system when a satisfactory signal is received by the latter system.

In certain prior art torpedoes wherein a gyro and pellet mechanism generally similar to that latter described is employed to control the azimuth steering engine, it has been the practice to employ a direct connection between gyro cam pawls of the pallet mechanism, which sense gyro axis orientation, and a pallet member whose angular deflection determines steering engine action, so that angular

2

lar deflection of the pawls in accordance with deviation of torpedo direction, from a preselected course, produced like deflection of the pallet member and corresponding corrective control of the steering engine.

5 In order to combine and adapt the prior art gyro and acoustic steering systems, taken by way of example and described in detail hereafter, to the dual control system of the present invention, the pallet mechanism is modified to provide a pallet member journaled on the pallet shaft and yieldably connected to an auxiliary pallet member clamped at the top of the pallet shaft, the aforesaid pawls being secured to the bottom of this shaft. Transmission of motion between the fixed pallet member and the journaled pallet member in response to the gyro control is accomplished by means of a hair pin spring which is connected therebetween and urges the two pallet members into alignment with each other, whereby the journaled pallet member is caused to yieldably follow movement of the fixed pallet member, the journaled member having secured thereto the pallet blade whose angular position controls the condition of the steering engine, and consequently, the angular position of the steering rudder.

A pair of solenoids employed in the acoustical system are arranged to also control the angle of setting of the pallet blade and thus control the rudder position in response to acoustic signals. This operation of the pallet blade, however, does not cause accompanying movement of the pallet shaft and resultant precession of the gyro for the reason that the aforementioned hair pin spring yields in response to driving movement of the journaled pallet member. Accordingly, the arrangement is such that the acoustic control system, in effect, "over-rides" the gyro control system and in a manner to prevent interference with the delicate balance of the gyro mechanism. Thus, if for any reason, the acoustical steering device becomes inoperative, the steering control is automatically returned to the gyroscopic control without having caused precession of the gyroscope during the acoustical control of the rudder position.

40 One of the objects of the present invention is to provide means for steering the torpedo under exclusive gyroscopic control in the absence of a satisfactory acoustical signal and at any time when a satisfactory acoustical signal is received by the acoustical steering device to transfer the control to acoustic response without causing precession of the gyroscope.

Another object of the present invention is to provide a yieldable linkage in the gyro controlled azimuth steering mechanism of a torpedo wherein an acoustically operated steering mechanism can override the gyroscopic control without introducing forces which will cause precession of the gyroscope or otherwise upset the delicately balanced mechanism which it comprises.

55 Still a further object of the present invention is to provide a steering device for a torpedo which is exclusively operated by a gyroscope in the absence of a satisfactory acoustical signal after the torpedo has started on the target run; is thereafter transferred from the gyroscopic control to acoustic control when the acoustic device receives a signal of predetermined intensity emanating from a target vessel; and thereafter is returned to the gyroscopic control should the acoustic device become inoperative for any reason.

60 Other objects and many of the attendant advantages of this invention will be readily appreciated as by reference to the following detailed description when considered in connection with the accompanying drawings wherein:

Fig. 1 is an expanded perspective view of a portion of the azimuth steering mechanism of a torpedo as employed in the steering system of the present invention and showing the cam plate and slide operating mechanism;

70 Fig. 2 is a perspective view of another portion of the

azimuth steering mechanism of a torpedo, certain portions being broken away and showing the azimuth steering engine and the driving connections thereto;

Fig. 3 is a somewhat enlarged plan view of the pallet mechanism having the yieldable link therein, which forms a connection between the gyroscope and acoustical steering mechanisms of the present invention;

Fig. 4 is a front view in elevation of the pallet mechanism of Fig. 3;

Fig. 5 is a plan view of the pallet mechanism and a pair of solenoid mechanisms which operate the pallet mechanism selectively to control the position of the steering rudder of the torpedo when a satisfactory signal is received by the acoustical steering mechanism;

Fig. 6 is a front view in elevation of the structure of Fig. 5; and

Fig. 7 is a longitudinal section through the axis of the torpedo and schematically illustrating the electrical circuit which operates to steer the torpedo when a satisfactory acoustical signal is received thereby.

Referring now to the drawings in which like numerals of reference are employed to designate like parts throughout the several views and more particularly to Fig. 1, there is shown thereon the cam plate 10 which is supported within the gyroscope housing (not shown) in such a manner that the cam plate lies in a horizontal plane within the housing. The axis of the gyro rotor is also set in a horizontal plane, and the cam plate 10 is mounted on top of the outer gimbal ring (not shown) of the gyroscope in such a manner that the cam plate and outer gimbal ring rotate together about a vertical axis as the longitudinal axis of the torpedo deviates from the axis of the spinning rotor of the gyroscope.

The cam plate 10 is provided with a port concentric ridge 12, port concentric groove 13, and similarly formed starboard concentric ridge 19 and starboard concentric groove (not shown) formed on the rim of the cam plate with the port groove lying in the horizontal plane of the starboard ridge and the starboard groove lying in the horizontal plane of the port ridge.

The port groove and ridge and the starboard groove and ridge are separated on the aft surface portion of cam plate 10 by a cam surface 15. The upper end of the gyroscope housing is enclosed by a suitable cover plate (not shown) on which is mounted the pallet mechanism, indicated generally at 22, which forms a connecting link between the gyroscope and the azimuth steering control mechanism, as will hereinafter be more fully described.

The pallet mechanism 22 includes a slide 17 which is reciprocated along the longitudinal axis of the torpedo and in a plane parallel to the cam plate 10 by a cam 24 which is rotated about its vertical axis by bevel gear 25 and pinion 26 as the torpedo driving motor (not shown) drives the torpedo through the water. A pair of spring loaded plungers 27 mounted on the gyro cover plate yieldably urge the slide 17 into engagement with the cam surface 24. Journalled in shaft holder 29 in the slide 17 is a vertically mounted pallet shaft 23 having a leaf spring 35 fitted into a slot provided therefor in the shaft to cause a slight drag between the shaft and the holder. Pinned to the lower end of shaft 23, at their hubs 38, are substantially diametrically opposed starboard cam pawl 36 and port cam pawl 37 which are offset along the pallet axis such that if pawl 36, for example, contacts cam 15 as the slide 17 and shaft 23 move together to the end of the forward stroke of the slide, further movement of these will rock the pallet shaft to an angular setting and, since pawl 37 lies on a plane with concentric groove 13, the pawl 37 will be accommodated in groove 13, and similarly, when pawl 37 touches the cam 15 as the slide 17 and shaft 23 moves to the end of the forward stroke, the pallet shaft will rock in the opposite direction and pawl 36, being on a plane with the starboard concentric groove, will be accommodated therein. As shown more clearly in Figs. 3 and 4, the ends of the pawls 36 and 37 are formed in the shape of hooks, the inner sides

14 of which are parallel to the axis of the hubs 38 and so dimensioned as to straddle cam 15 when the axis of the cam plate 10 is aligned with the longitudinal axis of the torpedo.

6 In order to provide an azimuth steering control mechanism which is operable in response to acoustical signals emanating from the rotating propellers of the enemy vessel, or ship noises, as the case may be, and which can "override" the aforescribed well known gyroscopic steering control of the torpedo, a yieldable linkage, generally designated 39 and best shown in Fig. 4, is mounted on the upper end of the pallet shaft 23. This linkage, as will appear more fully hereinafter, will not introduce forces into the gyroscopic steering mechanism when the torpedo responds to the acoustical steering device, thereby avoiding precession of the gyroscope during acoustical control.

Secured to the upper end of the pallet shaft 23, by set screw 42 as shown in Fig. 3 is an upper pallet member 41. Journalled on the pallet shaft 23 below the upper pallet member 41 is an actuating pallet member 43 which is yieldably connected to the fixed member 41 through a hair pin spring 44, the bight of which is taken around spring support 45 which is staked to the pallet member 43, with the radially extending arms 46 and 47 of spring 44 extending from spring support 45 to contact an upwardly extending pin 48 secured to pallet member 43 and a downwardly extending pin 49 secured to the upper pallet member 41. The action of spring 44 is such that pallet member 43 will yieldably follow the movement of fixed pallet 41 within limits determined by the tension of spring 44, and pallet member 43 may otherwise be rotated about pallet shaft 23 against the tension of spring 44 without affecting the position of the fixed pallet member 41, this being accomplished by reason of the drag on the pallet shaft caused by compression of spring 35 within the shaft holder 29.

Actuating pallet member 43 is provided with a pallet blade 51 which rotates with pallet member 43 about shaft 23 and extends aft, when mounted in the torpedo, and in a plane with the port pallet pawl 52 and the starboard pallet pawl 53, Fig. 2.

From the foregoing, it will be apparent that as the pawls 36 and 37 are moved to and from contact with the gyroscope cam plate 10, if the torpedo course differs on either side of the axis of the gyroscope one of the cam pawls 36 or 37, as the case may be, will move into line with and will contact the cam 15 and the other pawl will be accommodated in one of the concentric cam grooves, thereby to impart a slight rotary movement to the pallet shaft 23, which shaft extends through opening 50 on slide cover 57 with pallet members 41 and 43 and pallet blade 51 disposed on the upper side of the slide cover, and to cause pallet blade 51 to align with either the port or starboard pallet pawls 52 or 53, the angular setting of the blade 51 being determined by the turning motion imparted to the shaft 23.

As the pallet shaft 23 moves rearwardly with the slide 17 on the rearward stroke, pallet blade 51 is brought into contact with one or the other of the two spaced hook-shaped pawls 52 or 53, Figs. 2 and 5, depending on the angular setting of shaft 23. Pawls 52 and 53 are rotatably mounted on pivot pins 55 and 56 respectively on the slide cover 57. Pallet pawls 52 and 53 are cross-connected by links 58, 59 and adjusting screw 61 in such a manner that when port pawl 52 is rotated clockwise, as viewed in Fig. 5, by the pallet blade about pin 55, starboard pawl 53 is also moved clockwise about pin 56. In a like manner when the starboard pawl 53 is rotated counter clockwise about pin 56, port pawl 52 is rotated counter clockwise about pin 55. Stop pins 40 are provided to limit the rotary movement of pallet blade 51 and pawls 52 and 53, the extent of movement of the latter being controlled by the adjustment of screw 61. It is also to be observed that when there is substantial

parallelism of the torpedo longitudinal axis and the pre-selected course dictated by initial setting of the gyroscope axis direction, movement of the pawls 36 and 37 forwardly toward the cam plate will cause the pawls 36 and 37 to straddle the cam surface 15, and accordingly the pallet blade 51, when moved rearwardly on the backward stroke of the slide 17, will pass between the pallet pawls 52 and 53 and no rotary movement is imparted to pawls 52 and 53.

As seen more clearly in Fig. 2, port pallet pawl 52 is connected by a link 62, which is journalled at the lower arm portion of bell crank 63 for imparting an up and down movement to the other arm portion of the bell crank as pawl 52 rotates on pin 55, the bell crank 63 being pivoted in upstanding bracket 64 formed on the slide cover 57. The forward or other end of bell crank 63 is provided with a bifurcated portion 65 which, through suitable connection therewith, raises and lowers bell crank arm 66 which, in turn, through shaft 67 and arm 68 moves a connecting link 69 in a forward or rearward direction with respect to the torpedo axis. The connecting link 69 moves piston shaft 71 of an engine valve (not shown) enclosed within housing 28 in a forward or aft direction. Suffice it to say that as the piston shaft 71 moves the engine valve forward or aft, as the case may be, it opens suitable inlet ports to admit air under pressure to one side or the other of a piston (not shown) which is enclosed within housing 28, selectively to cause the piston and the link 72 connected to the piston to move in the opposite direction from the movement of piston shaft 71.

As the link 72 moves forward or aft, the steering rudder 78 operatively linked thereto as indicated at 54 is so positioned relative to the longitudinal axis of the torpedo as to impart an angular setting of the rudder to steer the torpedo in a port or starboard direction.

Referring now more particularly to Figs. 5 and 6, the present invention provides solenoids 81 and 82 having armatures 83 and 84 pivotally mounted on pivot pins 85 and 86 respectively. Armatures 83 and 84 are provided with rearwardly extending arms 87 and 88 arranged to engage their respective slide bars 91 and 92 which are mounted in suitable openings in relay bracket 93 for lateral sliding movement therein. Each of slide bars 91 and 92 are provided with springs 94 which urge the slide bars in an outward position against the end of arms 87 and 88.

Upon energization of one of the solenoids, such for example as solenoid 82, armature 88 moves inwardly to force slide bar 92 to the right as seen in Figs. 5 and 6, whereby the inner end of the slide bar 92 engages the pallet member 43 to apply a steering force to the yieldable link to rotate the free pallet in a clockwise direction, as viewed in Fig. 5, about the pallet shaft 23. The pallet blade 51 is thus oriented on pallet shaft 23 such that when the blade is moved rearwardly by action of cam 24 (Fig. 1), the blade engages the port pallet pawl 52 thereby to initiate a port steering movement of the steering engine.

The aforementioned acoustical steering mechanism disclosed and claimed in the patent issued to Robert S. Blair, Patent No. 1,588,932, may be employed for operating solenoids 81 and 82 which, as aforescribed, assume control of the steering mechanism of the torpedo when the solenoids are selectively operated, this being in response to compressional waves which operate the microphones in response to acoustical signals transmitted through the surrounding water by an enemy vessel, such waves being in the frequency range of the microphones. The torpedo may thus be steered to the target vessel under acoustical control, without causing precession of the gyroscope by reason of the yieldable linkage aforescribed.

Referring now more particularly to Fig. 7, there is shown thereon a torpedo casing 31 on the aft end of which is hinged the azimuth control rudder 78 on a verti-

cal axis normal to the longitudinal axis of the torpedo, the position of the rudder being controlled by the movement of the connecting linkage 72 and 54 (Fig. 2) in accordance with steering engine operation, as stated herefore, these being grouped as driving connections and indicated simply by the schematic link 113 in Fig. 7.

Disposed within the torpedo casing 31 is a storage battery 32, one terminal of which is connected through a conductor 33 to the coil of solenoid 81 and through a conductor 34 to the coil of the solenoid 82. The other terminal of the battery 32 is connected by a conductor 73 with an armature 74 which is pivoted at its center as indicated at 75. The pivoted armature 74 is provided at its ends with a pair of contact points 76 and 77. The contact point 76 on armature 74 is adapted to make contact with the terminal of conductor 111 which is connected to the other side of the winding of solenoid 82, and a circuit is completed from the battery 32 through this solenoid, to energize the solenoid, move arm 88 to the position as indicated in Fig. 5, which moves slide bar 92 and actuating pallet 43 to the right. As the pallet blade 51 moves rearwardly, it engages port pallet pawl 52 which through the connecting linkages, as heretofore described causes steering rudder 78 to be moved to the port steering position as will hereinafter be more fully described. Similarly, contact point 77 on armature 74 is adapted to make contact with the terminal of conductor 112 which is connected to the other side of the winding of solenoid 81, and a circuit is completed from the battery 32 through the solenoid 81 to move the rudder 78 to starboard steering position.

Positioned forwardly of the armature 74 is a battery 95, one terminal of which is connected to a conductor 96 which is connected to the terminals of carbon pile type microphones 101 and 102 respectively. The other terminal of the battery 95 is connected through a coil 103 and conductor 105 with the other terminal of microphone 101, and through a coil 104 and conductor 107 with the other terminal of microphone 102. The coil 103 is positioned about a core 108 forming part of the armature 74 so that when this coil is energized the armature 74 is swung to make contact at 77. Similarly, the coil 104 is positioned about a core 109 forming part of the armature 74 so that when this coil is energized, the armature 74 is swung to make contact at 76.

The microphones 101 and 102 are positioned adjacent the forward end of the torpedo preferably in recesses therein, as shown, and are responsive to vibrations such as sound waves received through the surrounding water. Sound waves striking any one of the microphones 50 compress the carbon pile thereof, lessening its resistance and permitting a current to flow therethrough from the battery 95 and energizing the coil through which the microphone is connected.

The two microphones 101 and 102 are preferably positioned in a plane substantially at right angles to the rudder 78, whose position they control through the connections aforescribed. It will be seen that sound waves striking the microphone 101, for example, cause a current to flow through the coil 103 which swings the armature 74, making contact at 77. This energizes the solenoid 81 which, as heretofore described, operates through the driving connections 113 including the steering engine to swing the rudder 78 to direct the torpedo in a starboard direction from which the sound waves are proceeding. In a like manner, sound waves striking the microphone 102 effect a turning of the rudder 78 to steer the torpedo in a port direction toward the source of these sound waves.

Thus the torpedo propelled through the water is automatically steered toward a source of sound. The torpedo will thus travel toward a moving vessel, the propellers or other sound source of which create a disturbance in the water, and will follow the vessel even though it travels in a changing course until it strikes the vessel

and explodes. When the torpedo is moving in the proper course, directly toward its target, the microphones 101 and 102 being symmetrically disposed receive the same intensity of sound wave from the target and the torpedo proceeds in substantially a straight path toward the target. Immediately, however, that the position of the source of sound changes with respect to the direction of movement of the torpedo, the rudder controlling mechanism is operated in response to the differing sound intensities to correct the direction of travel.

Should the energization force of the solenoids fail for any reason, the springs 94 will move their respective slide bars 91 and 92 to the initial outward or normal position, and spring 46 will again restore free pallet member 43 to a position of alignment with the fixed pallet member 41 and the torpedo will proceed under gyroscopic steering control, as heretofore described.

It thus becomes apparent that an azimuth steering control has been provided which is capable of inserting, into the control system, means for overriding the usual gyroscopic steering of a torpedo. The torpedo can thus be guided to a target vessel in response to acoustical signals emanating from the vessel without introducing forces into the gyroscope to cause precession and if, for any reason, the acoustic steering device fails to function the control may be returned to gyroscope steering.

Obviously many modifications and variations of the present invention are possible in the light of the above teachings. For example, the slide bars can readily be replaced with a U-shaped armature pivoted at the bight of the U and moved from one side to the other by a solenoid control against the tension of a centering spring. It is therefore to be understood that within the scope of the appended claims the invention may be practiced otherwise than as specifically described.

What is claimed as new and desired to be secured by Letters Patent of the United States of America is:

1. In a propulsive torpedo having steering means, in combination therewith: a gyroscopic mechanism including a pallet shaft controlled thereby to experience angular deflection, about the axis defined by said shaft, corresponding in sense to that of torpedo deviation from a preselected course direction; a pallet member journaled on said shaft and linked thereto, by resilient means, to normally experience the same angular deflection as said

- 45 pallet shaft; means for receiving target acoustic signals and for deriving therefrom control signals corresponding to target direction relative to torpedo heading; means responsive to said control signals to angularly deflect the pallet member independently of said pallet shaft deflection, through yielding action of said resilient means, and thus, during reception of said target acoustic signals, solely in accordance with deviation of the torpedo from target direction; and means for controlling said steering means in response to and in accordance with the angular deflection of said pallet member, to steer the torpedo along said preselected course direction in the absence of said target acoustic signals and to steer the torpedo towards said target during reception of said target acoustic signals.
- 15 2. In a propulsive torpedo having steering means, in combination therewith: a gyroscopic mechanism including a pallet shaft controlled thereby to experience angular deflection, about the axis defined by said shaft, corresponding in sense to that of torpedo deviation from a preselected course direction; a pallet member journaled on said shaft and linked thereto, by resilient means, to normally experience the same angular deflection as said pallet shaft; means for receiving target acoustic signals
- 20 25 and for deriving therefrom dual channel control signals having relative magnitudes corresponding to target direction relative to torpedo heading; means responsive to said control signals to angularly deflect said pallet member independently of said pallet shaft deflection, through yielding action of said resilient means, and thus, during reception of said target acoustic signals, solely in accordance with deviation of the torpedo from target direction; and means for controlling said steering means in response to and in accordance with the angular deflection of said pallet member, to steer the torpedo along
- 30 35 said preselected course direction in the absence of said target acoustic signals and to steer the torpedo toward said target during reception of said target acoustic signals.
